UNITED STATES PATENT OFFICE.

JAMES A. WHITCOMB, OF McALESTER, OKLAHOMA.

TYPE-WRITING MACHINE.

1,126,169.

Specification of Letters Patent. Patented Jan. 26, 1915.

Application filed June 6, 1910. Serial No. 565,311.

To all whom it may concern:

Be it known that I, JAMES A. WHITCOMB, a citizen of the United States, and a resident of the city of McAlester, in the county 5 of Pittsburg, State of Oklahoma, have invented certain new and useful Improvements in Type-Writing Machines, of which the following is a specification.

This invention relates broadly to type-10 writing machines and specifically to ribbon mechanism adapted particularly to type-writing machines of the folding type.

The principal object of this invention is to construct a ribbon mechanism in such 15 manner that the ribbon will be fed a definite distance during each movement of the key levers, the arrangement of parts being such that the ribbon spools and ribbon vibrator may be folded to abnormal posi-20 tions and the immediate key actuated mechanism will maintain its normal position in the typewriting machine.

Another object of the invention is to provide a ribbon mechanism particularly adapted 25 for a typewriting machine of the folding type, in which the ribbon spools are carried upon foldable members attached to the machine frame.

A still further object of the invention is 30 to provide a ribbon mechanism for a typewriting machine in which the platen carriage is shifted through an arc when it is moved from upper to lower case position, and the ribbon spools are adapted to be 35 moved together with the platen carriage.

A still further object of the invention is 40 to construct a ribbon mechanism for a typewriting machine in which the ribbon spools are directly actuated by a ratchet mechanism which is shiftable with the platen carriage to upper and lower case position.

A still further object of the invention is 45 to construct a simple spring which maintains both a holding dog and a movable dog in engagement with the ratchet wheel for operating a ribbon spool.

Other objects of this invention will be 50 obvious and others will be more specifically pointed out in the specification hereinafter 55 by reference to the accompanying drawings which form a part of this application, and will be more specifically defined in the claims.

In the specification and throughout the

several figures of the drawings, like numerals are used to indicate like parts.

Figure 1 is an elevation showing the ribbon spools when the carriage is in its folded relation. Fig. 2 is a longitudinal sectional elevational view taken substantially on line A—B of Fig. 3, with a portion of the type bar and carriage shifting mechanisms omitted. Fig. 3 is a transverse sectional elevation. Fig. 4 is a detail showing one ribbon spool in elevation. Fig. 5 is a detail view 65 showing both ribbon spools in elevation, and showing part of the means of actuation therefor. Fig. 6 is a detail plan view showing the ratchet mechanism for actuating the ribbon spools. Fig. 7 is an elevation taken 70 on lines C—D of Fig. 3, and shows the relationship of the ribbon mechanism to the platen shifting devices.

The typewriting machine illustrated in the drawings, and to which my ribbon mechanism invention is particularly adapted, is a typewriting machine of the folding type wherein side bars 1 and 2 are pivoted to a main machine frame 3, by means of stud bolts 5 and 6. The side bars 1 and 2 are so adapted to support a carriage bed 7, upon which a carriage frame 8 is mounted for reciprocal movement upon anti-friction rollers 9, 10 and 11, which are mounted on the carriage bed, and upon which a track rail 12 85 is adapted to reciprocate. The rear of the carriage frame is also provided with a track rail which co-operates with a grooved bed rail 15, fixedly mounted upon the carriage bed 7. The carriage frame is provided with 90 end frames 16 and 17, in which is mounted a cylindrical platen 18, and the usual line spacing mechanism 19. A series of key levers 20, 21 and 22 are mounted in the machine frame upon key lever supporting rods 95 24, 25 and 26, and are connected at their rear ends by means of links 27, with type bars 28, the type bars 28 being supported by means of hangers 29, attached to the rear walls of the main frame in a manner well known in the art. The key levers 20, 21 and 22 are provided with coiled springs 30, 31 and 32 respectively, which are connected with a portion of a type bar rest 34, in such manner as to return the key levers to normal position when a type bar has been actuated. The coiled springs 30, 31 and 32 are 100 105 protected by means of a front board 35,

which is attached to the machine frame by means of screws 36, and extends above the key levers from the right to the left wall of the typewriting machine frame. The front of the machine frame is supported upon a cross bar 37, which is provided with rubber feet 38. The cross bar 37 performs the double function of providing means for stiffening the front of the machine frame, and also providing a sufficient width of surface upon which to attach the rubber feet 38. At the rear corners of the machine frame, plates 39 and 40 are provided, in a manner similar to the cross bar 37, and form a bracing for the corners of the machine frame and also provide a sufficient supporting surface for mounting the rubber feet 41 and 42, upon which the rear of the machine is supported. A space bar 44, is mounted, immediately in front of the letter keys on the key board, upon rearward extensions 45, which are bifurcated at 46, in such manner as to guide a universal bar 47, which is constructed of a sufficient length to cover all of the ends of the key levers, as is shown particularly in Fig. 3. The universal bar 47, is mounted upon links 48 and 49, which are provided with pairs of lock nuts 50 and 51, by means of which the universal bar 47 may be properly adjusted a definite height above the rear ends of the key levers. It is desirable that the universal bar be some little distance above the key levers that are connected with the type bars, for the reason that upon depressing a key lever the only force necessary to be exerted is a weight sufficient to start the type bar in its upward movement toward the printing point, and the type bar will have gained considerable momentum before the key lever contacts with the universal bar. Thus it will be seen that the mechanisms, hereinafter to be described, which are operated by the universal bar, are not brought into operation until a certain amount of energy has been stored in the bar mechanism because of the momentum of the moving type bar, and thus less actual weight will be required to operate the universal bar and attendant mechanisms than if the universal bar were placed immediately upon the ends of the key levers. The links 48 and 49 are provided with hooked-shaped portions 52 and 54, which are adapted to be engaged with openings in bell crank levers 55 and 56, pivotally mounted upon brackets 57 and 58, which are attached to the rear wall of the machine main frame. The bell cranks 55 and 56 carry T-shaped headed studs 59 and 60, which operate with vertical lever links 61 and 62. The lever links 61 and 62 are pivotally mounted upon a rod 64, that is supported upon the platen shift bell cranks 65 and 66, and which will be more specifically described hereinafter. The vertical levers 61 and 62 are provided with slotted openings 67 and 68, through which the T-shaped headed studs 59 and 60 extend, in order to communicate motion from the universal bar to the vertical lever links. Leaf springs 69 and 70, are fixedly mounted upon the rear wall of the machine frame and bear against the vertical lever links 61 and 62 respectively, in such manner as to force these links toward the front of the machine and to cause the universal bar to press downwardly against the base of the bifurcated forks 46. A transverse bar 71, is riveted to rearward extending portions of the vertical lever links 61 and 62 and securely connects the upper portions of the two vertical links together. A sliding collar 72 is mounted upon a transverse bar 71, and is adapted to contact with a bell crank arm 74, which is pivoted to the carriage bed. One arm of this bell crank lever 74 is in engagement with a notched portion 75 of the ribbon vibrator arm 76, which is retained in normal position by means of a small coiled spring 77. The ribbon carrying spools are mounted in front of the carriage bed upon the side bars 1 and 2, and are built from composite parts, which will now be more specifically described. Vertically extending shafts 78, are set in the side bars 1 and 2, and are adapted to carry hollow shafts 79, to which ratchet wheels 80 and 81 are fixedly attached. Collars 82 are adapted to set upon the lower portion of the hollow shafts 79, and rest upon a small shoulder provided upon the hollow shafts 79, just above the ratchet wheels. Ribbon guide bases 84 and 85, are fixedly attached to the side bars 1 and 2, by means of small stub screws which engage the side bars. The ribbon guide bases 84 and 85 are provided with openings through which the hollow shafts hereinbefore described, are adapted to extend. At the rear of the ribbon guide bases there are small upward extending arms 86, which prevent the ribbon from coming in contact with the platen cylinder. The guide bases are also provided with guide members 87 and 88, through which the ribbon is adapted to be fed to the ribbon vibrator 76. The ribbon spools 89 comprise single ended spools which are adapted to be positioned over the hollow shafts and pass through openings in the ribbon guide bases and contact with the upper ends of the collars 82. Right and left hand threaded check nuts 90 and 91, are adapted to clamp the ribbon spools upon the collars 82. When either of the check nuts 90 or 91 is tightened sufficiently to prevent the ribbon spool from turning upon the collars 82, it will be seen that the ratchet wheel 80, the collars 82, the hollow shaft 79, and the ribbon spool 89, will all turn together upon the vertical shaft 78. Right and left hand retaining dogs 92 are mount- 130

ed upon the side bars 1 and 2 respectively, and are adapted to engage the teeth in the ratchet wheels 80 and 81 respectively. The retaining dogs 92 are mounted in front of the ratchet wheels, and bell crank levers 94 and 95 are also respectively mounted upon the side bars 1 and 2, to the rear of the ratchet wheels 80 and 81. The bell crank levers are adapted to carry upon one arm 10 of the bell crank, actuating dogs 96 and 97. All of the dogs, including both the retaining dogs and the actuating dogs, are provided with upward extending portions through which the ends of the springs 98 and 99 are adapted to pass, and thus force the dogs into their operative relation with the teeth of the ratchet wheels. Each of the bell cranks 94 and 95, is provided with an extended portion which is adapted to 20 contact with the carriage bed in order to properly stop the movement of the bell cranks 94 and 95 when under the influence of the springs 98 and 99. Each of the bell cranks 94 and 95, is provided with an inwardly extended arm 100, that extends into the path of the upper ends of the vertical lever links 61 and 62, and each of the extending portions of the arm 100 is guided in its path by means of a small bracket 101, 25 that is mounted upon the carriage bed.

From the hereinbefore described structure, it will be seen that for each actuation of the printing key levers, the universal bar is raised and through the several connected links and bell cranks, the vertical lever links 61 and 62 are swung at their upper ends toward the rear of the machine frame, and in this rearward movement the upper ends are in contact with the extended arms 40 of the bell crank levers 94 and 95, thus causing the bell cranks to be actuated and each ratchet wheel to be turned a distance of one tooth on its periphery. It will also be apparent that both the ratchet wheels 80 and 81, are simultaneously rotated, but that the direction of motion is different in each wheel. In order that the ribbon may be moved from one spool to the other spool, it is necessary that one of the check nuts 90 or 91, be screwed down solidly upon its respective ribbon spool and the other check nut be left loose in order that the ribbon spool may be allowed to turn upon the hereinbefore described hollow shaft. When it is desirable to reverse the longitudinal motion of the ribbon, the check nut which has been tightly seated, is unloosened, and the check nut which has been loose is screwed down tightly upon the ribbon spool.

The side bars 1 and 2, are shifted from upper to lower case, and to a third position for figures and characters, by a mechanism which will now be more specifically described. To the left of the key board there are located two keys, i. e., 102 and 104,

which are mounted upon key levers 105 and 106 respectively. These key levers are carried upon the key supporting rods 24 and 26 respectively. The key lever 105 is connected by means of the link 107, with the platen shift bell crank 64, by means of a pin-and-slot connection. The shift key 106 is also connected by means of a link 108, to the platen shift bell crank, and the connection in this case is also made by a pin-and-slot connection. A cam actuated stop member 109 is pivoted to the machine side frame at a point 110, and at its upper end carries two adjustable stop screws 111 and 112. The forward portion of the cam actuated stop member is provided with a cam face 114, which is adapted to coöperate with a pin 115, carried in the outer end of the key lever 106. The bell crank shift key levers 65 and 66, are connected at their upper ends with coiled springs 116, that are fastened to brackets 117, which are attached to the side frames of the typewriting machine. The coiled springs 116 are of a sufficient strength to substantially counterbalance the weight of the carriage and attending mechanisms which are shifted when the shift mechanism is operated. Upwardly extending shift links 118 and 119, are carried by the outer ends of the platen shift bell cranks upon the transverse rod 64, which rod also carries the vertical lever links 61 and 62. The upwardly extending shift links 118 and 119, are each provided with a slot 124, through which are adapted to extend T-shaped headed stud blocks 120 and 121, which form guiding pivots to direct the motion of the upwardly extending shift links 118 and 119 when they are shifted in the platen shifting operation. The upper ends of the shift links 118 and 119 are bifurcated and coöperate with pin studs 122, which are fixedly mounted in the side bars 1 and 2 respectively. The shift link 119 is provided on its upper end with a latch member 125, which prevents the side bars, carriage mechanism, ribbon mechanism, etc., from being accidentally folded when the machine is carelessly lifted and turned upside down. The front edge of the shift link 119 is bent over to form a stop 126, which stop is adapted to coöperate with either of the adjustable stop screws 111 and 112, depending upon which screw is positioned in the path of the stop. The cam face 114 on the cam actuated stop member 109, is maintained in engagement with the pin 115 on the key lever 106, by means of a leaf spring 127, which bears upon the rear face of the cam actuated stop member, and is attached at its other end to the rear wall of the machine frame.

From the hereinbefore described mechanisms, it will be noted that the ribbon spools are carried upon the side bar arms which

form a folding support for the carriage bed, feed mechanism, etc., and which side bars are pivoted directly to the machine frame. Therefore, when the carriage and actuated mechanisms are folded over, the ribbon spools, and the ribbon mechanism is also folded and occupies a relationship over the keys of the key board, which is substantially that illustrated in Fig. 1. Furthermore, the ribbon spools and the attending actuating mechanisms, are shifted with the platen carriage through an arc, the center of which is a point of the machine frame, when the platen carriage and attendant mechanisms are shifted from upper to lower case.

Having thus described my invention what I claim as new and desire to secure by Letters Patent is:—

1. In a typewriting machine, the combination of a machine frame, side bars pivotally mounted upon said machine frame, carriage mechanism mounted upon said side bars, ribbon spools carried by said side bars, means for shifting said ribbon spools and carriage mechanism to upper and lower case, vertically extending lever links carried by said shifting mechanism, bell crank dog carriers arranged to be actuated by said vertically extending lever links, key levers mounted in said machine frame, operative means connecting said key levers and said vertically extending lever links, and operative means connecting said bell crank dog carriers with said ribbon spools, substantially as described.

2. In a typewriting machine, the combination of a machine frame, side bars pivotally mounted upon said machine frame, carriage mechanism carried by said side bars, ribbon spools mounted upon said side bars, key levers mounted in said machine frame, a universal bar extending over said key levers, bell crank members, links connecting said bell crank members with said universal bar, and operative means connecting said bell cranks with said ribbon spools, substantially as described.

3. In a typewriting machine, the combination of a machine frame, side bars pivotally mounted upon said machine frame, ribbon spools mounted upon said side bars, finger keys, type bars, connections between said key levers and said type bars, the upper ends of said connections being normally below the upper edges of the sides of the machine frame, a universal bar mounted over said key levers but out of contact therewith, and operative means connecting said key levers and said ribbon spools, substantially as described.

4. In a typewriting machine, the combination of a machine frame, side bars pivotally mounted upon said machine frame, carriage mechanism carried by said side bars, key levers mounted in said machine frame,

means for shifting said side bars to upper and lower case positions, ribbon spools mounted upon said side bars, a universal bar mounted in operative relation to but out of contact with said key levers, and connecting means between said universal bar and said ribbon spools, said connecting means including bell-cranks mounted upon the top of the side parts and having inwardly and downwardly projecting arms, substantially as described.

5. In a typewriting machine, the combination of a machine frame, side bars pivotally mounted upon said machine frame, carriage mechanism mounted upon said side bars, ribbon spools carried by said side bars, means for shifting said ribbon spools and carriage mechanism to upper and lower case positions, vertically extending lever links carried by said shifting mechanism, operative means connecting said vertically extending lever links with said ribbon spools, key levers mounted in said machine frame, type bars operatively connected with said key levers, a universal bar extending over said key levers and out of contact therewith, and operative means for connecting said universal bar with said vertically extending lever links, said operative means including bell-cranks mounted upon the top of the side parts and having inwardly and downwardly projecting arms, substantially as described.

6. In a typewriting machine of the folding type, the combination of a machine frame, side bars pivotally mounted to the upper portion of said machine frame, carriage mechanism carried by said side bars, ribbon spools mounted upon said side bars, means for operating said ribbon spools when said side bars are in normal position, and means for shifting said carriage mechanism and said ribbon spools through the segment of an arc to position said carriage mechanism for upper and lower case printing, substantially as described.

7. In a typewriting machine, the combination of a machine frame, side bars pivotally mounted upon said machine frame, vertically extending shafts fixedly mounted upon said side bars, hollow shafts mounted for rotation upon said fixedly mounted shafts, ratchet wheels fixedly mounted upon said hollow shafts, means for actuating said ratchet wheels, and ribbon spools loosely mounted upon said hollow shafts, substantially as described.

8. In a typewriting machine, the combination of a machine frame, side bars pivotally mounted upon said machine frame, vertically extending shafts fixedly mounted upon said side bars, hollow shafts mounted for rotation upon said fixedly mounted shafts, ratchet wheels fixedly mounted upon said hollow shafts, ribbon spools mounted for rotation upon said hollow shafts, means for

clamping said ribbon spools in such manner that they may be made to rotate with said hollow shafts, and means for actuating said ratchet wheels.

5 9. In a typewriting machine, the combination of a machine frame, side bars pivotally mounted upon said machine frame, vertical shafts fixedly mounted upon said side bars, rotative means mounted upon said fixedly 10 mounted shafts, ribbon spools carried by said rotative means, ratchet wheels operatively connected with said rotative means, bell crank actuating levers, and actuating dogs carried upon said bell crank actuating 15 levers, substantially as described.

10. In a typewriting machine, the combination of a machine frame, side bars pivotally mounted upon said machine frame, ribbon spools carried by said side bars, actuating 20 means for said ribbon spools, said actuating means including ratchet wheels, bell crank actuating levers, actuating dogs carried upon said bell cranks, holding dogs carried upon said side bars, and means for 25 causing said actuating dogs and said holding dogs to engage said ratchet wheels, and means for operating said bell crank actuating levers.

11. In a typewriting machine, the combination of a machine frame, side bars pivot-

ally mounted upon said machine frame, ribbon spools carried upon said side bars, means for actuating said ribbon spools, said actuating means comprising bell cranks pivotally mounted upon said side bars, actuating dogs 35 carried upon said bell cranks, holding dogs pivotally mounted upon said side bars, and a spring member for each ribbon spool, said spring member being adapted to engage the actuating dog and the holding dog for each 40 ribbon spool, substantially as described.

12. In a typewriting machine, the combination of a machine frame, side bars pivotally mounted upon said machine frame, key levers mounted in said machine frame, type 45 bars, connecting links between said key levers and said type bars, a spacing key lever which terminates at its rear end in a bifurcated portion, a universal bar, said bifurcated portion of said spacing key lever being adapted 50 to carry said universal bar above and out of contact with said key levers, ribbon spools carried upon said side bars, and operative means connecting said universal bar and said ribbon spools, substantially as described.
